Patented June 15, 1976

240,305

COMBINED AQUARIUM AERATOR AND ORNAMENT HOLDER

Bernard Suchowski, Marlboro, David D. Lovitz, Short
Hills, and Claud W. Kissin, Fort Lee, N.J., assignors to
The Hartz Mountain Corporation, Harrison, N.J.

Filed Jan. 30, 1975, Ser. No. 545,627

Term of patent 14 years

Int. Cl. D30—99

U.S. Cl. D30—12

FIG. 1

FIG. 2

FIG. 3

FIG. 5

FIG. 4

FIG. 6

FIG. 1 is a perspective view of a combined aquarium aerator and ornament holder showing our new design;

FIG. 2 is a top plan view;

FIG. 3 is a front elevational view;

FIG. 4 is a right side elevational view;

FIG. 5 is a rear elevational view; and

FIG. 6 is a bottom plan view.

We claim:

The ornamental design for a combined aquarium aerator and ornament holder, as shown and described.
